UNITED STATES PATENT OFFICE.

SILAS HAMMOND STROWBRIDGE, OF CORTLAND, NEW YORK, ASSIGNOR TO
LYDIA A. STROWBRIDGE, OF SAME PLACE.

POSITIVE SHUTTLE-MOTION FOR LOOMS.

SPECIFICATION forming part of Letters Patent No. 417,687, dated December 17, 1889.

Application filed February 18, 1889. Serial No. 300,380. (No model.)

To all whom it may concern:

Be it known that I, SILAS HAMMOND STROWBRIDGE, a citizen of the United States, residing at Cortland, in the county of Cortland and State of New York, have invented certain new and useful Improvements in Positive Shuttle-Motions for Looms, of which the following is a full, clear, and exact description.

10 My invention relates to positive shuttle-motions for looms for weaving wire-cloth, and the specific improvements relate to certain mechanism whereby the shuttle is carried from one side to the other, and in the details 15 of the construction of the carrier-arms.

The object of the invention is to provide a simple and effective means for automatically releasing one end of the shuttle at the same instant of time that the other end is engaged 20 by the other arm. This object I attain by the mechanism illustrated in the accompanying drawings, which form a part of this specification, and in which—

Figure 1 represents a front elevation of a portion of a loom, showing my improvements applied thereto, parts being shown in section. Fig. 2 represents a vertical section of the carrier-arms, their attachments, and the shuttle.

Similar letters refer to similar parts in both 30 views.

The letter A indicates the beater-bars; B, the carrier-arms, and C the shuttle. A sliding bar D, having beveled ends D' D'', is located underneath the lower beater-arm.

35 E E' are vertical sliding bars, which act as stops against which pins F F', carried by the carrier-arms, strike to release the shuttle from engagement with first one and then the other carrier-arm, as will be more fully hereinafter 40 described.

G G' are vertical bars secured to and made a part of the sliding bar D. These bars extend above the carrier-arms in such a manner that a shuttle, as it moves across the 45 width of the loom, will come in contact with the said bars.

Located within each of the carrier-arms are spring-catches H and auxiliary spring-catches H', adapted to engage the shuttle by means 50 of slots or holes K K', made in each end of the shuttle. These catches are provided with

lugs h h, having inclined sides, the purpose of which will presently appear. The engaging ends of the catches operate in slots made in the carrier-arms after the usual manner. 55 Also located within the carrier-arms are sliding rods I I', each provided at one end with a rectangular block i, and at the other end with a wedge-shaped block i', for the purpose of acting upon the inclined faces of the lugs h h 60 to force apart the spring-catches and thereby release the end of the shuttle when the sliding rod is forced backward. Coiled springs m are located in the rear of the blocks i, the function of which will be hereinafter explained. 65

The pins F F' project outward from the blocks i through slots c in one side of the carrier-arms and engage the vertical bars E E' when they are forced upward by the action 70 of the beveled ends of the sliding bar D.

One of the principal features of the invention is the employment of the auxiliary or safety spring-catches, the object of which is to provide against accidents that frequently 75 occur by the breaking of or the getting out of order of the spring-catches.

The slots K' are made longer than the slots K, so that when catch H engages the shoulder of slot K the catch H' will have no engaging effect with slot K'; but if catch H should break or become inoperative from any cause the catch H' would engage the shoulder of the slot K', and thus insure the safe 80 and continuous operation of the shuttle. 85

It will be observed that the spring-catches, instead of being located within the carrier-arms, may be attached to the outside thereof, the engaging ends working through the usual 90 slots in the arms.

The means for actuating the carrier-arms is not shown; but any one of the several well-known means may be employed—such as, for instance, that shown in the patent granted to Benjamin Northrup, dated August 9, 1887, 95 and numbered 367,838, with the exception that instead of mounting the crank-arms on the actuating-shaft in the manner shown in the drawing of the said patent I mount the said arms one hundred and eighty degrees 100 apart on said shaft.

The operation of the device is as follows:

- Motion being imparted to the actuating mechanism, as the shuttle moves backward from the center of the loom toward the right-hand side it engages the vertical bar G', sliding the 5 bar D, the beveled end of which as it moves to one side raises the vertical bar E', the opposite end allowing the bar E to drop below the carrier-arm, as shown in Fig. 1 of drawings. Then as the carrier-arms move forward to 10 ward the center the pin F' comes in contact with the raised vertical bar E', holding back the sliding rod I, and as the wedge-shaped block i comes between the lugs h h it forces apart the spring-catches at the moment the 15 opposite end of the shuttle comes in contact with the spring-catch H in the other carrier-arm, which is not operated upon at this time by reason of the vertical bar E having been dropped below the carrier-arm, the sliding 20 bar D being only of sufficient length to engage one of the vertical bars E E' at a time. The shuttle being thus released by the forcing apart of the spring-catches in one of the carrier-arms is caught by the catch in the 25 other carrier-arm and carried to the other side of the loom, where it operates upon the mechanism in the same manner as above described, and the operation is repeated. When the sliding rods E E' are not engaged by the 30 pins i, the wedge-shaped blocks are held away from the lugs h h by the coil-springs m.
- Having thus fully described my invention, what I claim as new, and desire to secure by Letters Patent, is—
- 35 1. The combination of a shuttle, a carrier-arm, a spring-catch, a sliding rod carrying a wedge-shaped block adapted to actuate said catch to release the shuttle, and provided with a projecting pin, a sliding bar having 40 an arm in the path of the shuttle and formed with a beveled end, and a sliding bar adapted

to be moved by said beveled end and be engaged by the projecting pin on said shuttle-rod, substantially as specified.

2. The combination of a shuttle, carrier-arms, spring-catches, sliding rods provided with wedge-shaped blocks adapted to actuate said catches to release the shuttle, and provided each with a projecting pin, a sliding bar having arms in the path of the shuttle 45 and formed with beveled ends, and sliding bars adapted to be moved by said beveled ends into the paths of the projecting pins on said wedge-shaped blocks, substantially as specified.

3. The combination, with a carrier-arm having its ends adapted for the reception of one end of the shuttle, of a pair of spring-catches secured to said arms and provided with lugs h h on their adjacent sides, one of said catches 60 adapted to serve as a safety-catch in holding and permitting the continued operation of the shuttle in the event of the breakage of the other, a sliding rod carrying a wedge-shaped block adapted to enter between the 65 lugs on the catches to effect the separation of the latter, and means for actuating the sliding rod carrying the wedge-shaped block, substantially as specified.

4. The combination of a shuttle, the carrier-arms B, the spring-catches H H', the sliding rods I I', adapted to actuate said catches to release the shuttle, and provided each with a projecting pin F and F', respectively, sliding bar D, carrying arms G G' and formed with beveled ends, and sliding bars E 70 E', substantially as specified.

SILAS HAMMOND STROWBRIDGE.
